UNITED STATES PATENT OFFICE.

SAMUEL MURTA, OF ST. LOUIS, MISSOURI.

WATER-ELEVATOR.

1,227,180.

Specification of Letters Patent. Patented May 22, 1917.

Application filed July 14, 1913. Serial No. 778,893.

To all whom it may concern:

Be it known that I, SAMUEL MURTA, a citizen of the United States of America, and a resident of the city of St. Louis and State of Missouri, have invented certain new and useful Improvements in Water-Elevators, of which the following is a full, clear, and exact description, reference being had to the accompanying drawings, forming a part of this specification.

My invention relates to water elevators wherein a fluid under pressure is utilized to lift water, the present invention being an improvement on the water elevator shown in Patent Number 1,016,085, issued to me January 30, 1912.

The object of the present invention is to produce a water elevator operable by compressed air and which is so constructed that the air pressure is initially exerted on a descending column of water, the water being forced downwardly in a pressure pipe, through an ejector, and then upwardly so as to draw water from a well, located below the ejector. The pressure pipe is supplied with water through the medium of a return pipe by which a portion of the elevated water is returned to the ejector.

Figure I is a vertical section of a water elevator embodying the features of my invention.

Fig. II is an enlarged vertical section taken through the ejector.

In the drawings:

1 designates a discharge pipe secured to an ejector 2 and extending to a point above a reservoir 3. A pressure pipe 4, surrounding the discharge pipe, is seated on the ejector 2 and provided at its upper end with a stuffing box 5 through which the discharge pipe passes. The pipes 1 and 4 as well as the ejector 2 are surrounded by a return pipe 6 which terminates at an abutment 7. 8 and 9 designate intake pipes located below the abutment 7, the pipe 9 being provided with inlet openings 10. 11 is a delivery pipe for conducting water to the ejector 2. The upper end of the pipe 11 is located in the ejector 2 and its lower end is slotted for the admission of water at points below the ejector 2. A float 12 arranged in the delivery pipe 11 is connected to a check valve 13 by a stem 14. 15 designates a valve seat located below the check valve 13. In the practical use of my water elevator, air under pressure is delivered through an

air supply pipe 17, provided with a check valve 17^a, from a suitable pump P to the upper end of the pressure pipe 4 and the water in the pipe 4 is forced downwardly through the slots 16 in the ejector, out through the ejector and upwardly in the discharge pipe 1 thereby creating a suction in the intake pipes 8 and 9, which draws water from the well W through the ejector 2, into the discharge pipe 1 and discharges said water into the reservoir 3. A portion of the water delivered to the reservoir passes out through the overflow pipe 18 and the remainder is permitted to return through pipe 19 to the return pipe 6. 20 designates a check valve for preventing the water from being forced upwardly in pipe 19. When the pressure is relieved to stop the flow of water, the check valve 13 closes automatically to prevent the elevated water from returning to the well. This relief may be effected by stopping the pump and opening the relief port 17^b of check valve 17^a by hand. The water in the return pipe 6 replaces the air in pressure pipe 4 and the water in the pipe 19 and part of the water in the reservoir replaces the water in the return pipe. The pressure pipe is thus immediately charged with water for the next operation of the apparatus. Any suitable check valve provided with a relief may be used, such for instance as that of patent to Horne No. 372071, already public property.

The inlet ports 16 of the ejector 2 are so formed that the telescoping pipes 1, 4 and 6 communicate with each other, said ports being extended downwardly below pipe 4 to communicate with pipe 6. It will therefore be understood that the water in these pipes tends to seek a common level as shown in Fig. I; and that balanced columns of water are present in the three pipes 1, 4 and 6 when the air pressure is shut off. The water is placed in motion by the application of pressure to the top of one of the balanced columns of water, namely, the column of water between pipes 1 and 4. The water in the discharge pipe 1 rises as the water between pipes 1 and 4 descends, and the water elevated in pipe 1 is discharged into the reservoir 3. As the weight of the water to be discharged is initially balanced by other columns of water it will be readily understood that a slight degree of pressure on one of the last named columns of water will raise the water level in the dis-

charge pipe, so that the water will readily flow from the discharge pipe 1 in response to the air pressure in the pipe 4. This is particularly desirable in starting the flow of water from deep wells for it is an advantage in starting the circulation to apply the air pressure to the top of a column of water, instead of merely forcing air through the ejector.

10 The operation and advantage are comparable to the ancient practice and advantage of pouring water into the top of a pitcher pump when starting the pumping operation, the water furnishing a solid body, better 15 adapted to produce an immediate and sure suction, by reason of its weight and non-attenuability, in pipes of a diameter suitable for pumps of this character, than a gaseous body such as air, which, owing to its attenuability requires considerable effort to produce the vacuum necessary to start a circulation of water, although after a circulation is produced, the air body is convenient as a 20 continuous inspirator of the circulation, additional body and weight being given as needed by the water through pipes 6 and 19. As in the case of siphons the circulation when once started is easy of continuance, the 25 suction being advanced by the siphonic pull of pipe 1.

The return pipe 6 serves as a storage compartment for confining a body of water which is to be used in balancing the columns of water in pressure pipe 4 and discharge pipe 1 when the air is shut off. This pipe 6 also serves as a convenient means for conducting water to the lower end of the ejector 2. A stand pipe 21 is preferably, but not essentially, connected to the return pipe 40 6, said stand pipe being extended upwardly

to a point where it will confine a column of water extending to a plane near the upper end of the discharge pipe 1. The water in stand pipe 21 aids in balancing the water in the discharge pipe 1. The stand pipe also 45 serves as a vent, permitting the water to rise or fall in the return pipe 6 after the air pressure has been shut off.

When the air pressure is shut off, the check valve in the pressure pipe 17 may 50 be readily opened by hand, to relieve the pressure in pipe 4, thereby allowing the water to flow downwardly in pipes 6, 19 and 21, and upwardly in the pipe 4. The water in pipes 1, 4 and 6 then seeks a common 55 level to constitute the balanced columns of water to which I have previously referred.

I claim:—

In a water elevator, the combination of an ejector, a discharge pipe leading therefrom, 60 a pressure pipe leading thereto, a return pipe in communication with the ejector, an air supply pipe, a check valve in said air supply pipe, a relief device whereby the air in the pressure pipe may be exhausted when the ejector is not in operation, a reservoir located beneath the outlet end of the discharge pipe, a pipe communicating between the reservoir and the return pipe, and a 65 check valve in said pipe, whereby the pressure pipe may be recharged with water as the air is exhausted from the pressure pipe and the elevator be started with a water charge impelled by air under pressure and 70 its operation continued without interruption by air under pressure.

SAMUEL MURTA.
